UNITED STATES PATENT OFFICE.

BRADLEY HASKINS, OF MILWAUKEE, WISCONSIN, ASSIGNOR, BY MESNE ASSIGNMENTS, TO ALLIS-CHALMERS MANUFACTURING COMPANY, A CORPORATION OF DELAWARE.

SWITCH.

1,120,382.

Specification of Letters Patent.

Patented Dec. 8, 1914.

Application filed May 15, 1911. Serial No. 627,203.

To all whom it may concern:

Be it known that I, BRADLEY HASKINS, a citizen of the United States, residing at Milwaukee, in the county of Milwaukee and 5 State of Wisconsin, have invented certain new and useful Improvements in Switches, of which the following is a full, clear, and exact specification:

My invention relates to electric switches. 10 The primary object of my invention is to improve and simplify certain existing types of oil switches, especially those in which the switch parts proper are removable as a unit from the oil tank without disturbing 15 the latter or the line terminals within it.

It is further my object to provide a novel form of double throw switch and a new form of contact.

The various novel features of my invention will appear from the description and drawings and will be particularly pointed out in the claims.

Figure 1 is a section substantially on the line 1—1 of Fig. 3, the switch being in open 25 position and some of the parts being broken away on other section lines; Fig. 2 is a section substantially on the line 2—2 of Fig. 1, but with the removable unit partly raised; Fig. 3 is a section substantially on the line 3—3 of Fig. 1, the switch being in closed 30 position; Fig. 4 is a section substantially on the line 4—4 of Fig. 3, the switch being open; and, Fig. 5 is a section substantially on the line 5—5 of Fig. 2.

35 The frame 10 may be arranged for mounting in any desired manner, as on a floor or a switch-board. It carries all the parts of the switch. Hanging from the frame 10 is the oil tank 11, which contains oil in which all the live parts of the switch are immersed and in which all making and breaking of the circuits takes place. Two bars 12 extend longitudinally of the tank near the lower corners thereof, these bars 40 being supported by bolts 13 depending from the frame 10. Connecting the two bars 12 are a plurality of cross-bars 14, one cross-bar for each pole of the switch; the switch shown is a three-pole switch. Mounted on each cross-bar 14 are three porcelain insulators 15, in the top of each of which is embedded the shank of a wedge-shaped switch terminal 16. The insulators 15 are preferably corrugated circumferentially to increase the creepage distance between the

switch terminals 16 and the bar 14. Soldered in a suitable opening in each terminal 16 is a conductor lead 17. The leads 17 extend in a horizontal plane to the two sides of the tank, where they turn upwardly and 60 extend through insulating bushings 18, located in suitable holes in the frame 10, to the line conductors 19, being connected to the latter by suitable couplings 20 within the bushings 18. The leads from the outer 65 switch terminals 16 on each cross-bar 14 extend from the switch terminals directly outward until they reach the plane of the bushings 18, the bushings corresponding to these outer terminals being in line with the 70 terminals themselves. The leads from the middle terminals on the several cross-bars 14 are bent in the plane of the switch terminals so that they extend to three end bushings 18, as clearly shown in Fig. 5.

75 Supported on inwardly extending lugs 21 from the frame 10 is a removable frame 22 which carries the switch parts proper. This removable frame comprises two metal end plates 23 connected at the bottom by a plate 24 of insulating material. The plate 24 is preferably of molded insulating material, and has molded in it I-shaped metal pieces 25, the enlarged ends of which are located above and below the plate 24. These I-shaped pieces 25 correspond in number with the switch terminals 16 and are respectively located directly over them and have opposed spring contact fingers 26 attached to their enlarged lower ends and similar fingers to their upper ends. When the removable unit is in place, the opposed contact fingers 26 on each piece 25 engage the two sides of the corresponding wedge-shaped switch terminals 16, as illustrated in Fig. 1. 80 The lower surface of the plate 24 is provided with crossed ribs 28 to increase the creepage distance between adjacent sets of contact fingers 26. Integral with or attached to the upper surface of the plate 24 is a set of insulating barriers or partitions 29, which are so located that each set of contact fingers 26 is in a separate compartment, as best illustrated in Fig. 4. The barriers between the contacts for different phases preferably extend higher than do the barriers between contacts for the same phase.

85 The contact fingers 26 above the plate 24 co-operate with movable contacts 30 mount- 90 95 100 105 110

ed on the lower ends of bridge member 31 clamped on an insulator 32 molded or otherwise fixed on a rod 33. There is one bridge member 31 with its two contacts 30 for each pole of the switch the bridge member and its contacts together forming a bridging contact which coöperates with the corresponding contacts 26 to connect the middle one to either one of such contacts. 10 The ends of the rod 33 are fixed to the upper ends of cross-heads 34, the lower ends of which are fixed to short rods 35. These rods extend through and carry rollers 36 fitting in slots 37 in the respective end plates 23. The end portions of these slots are vertical and parallel, and are connected by inverted V-shaped portions. Fixed to the ends of the rods 35 outside of the end plates 23 are upwardly extending arms 38 carrying at their upper ends stub-shafts 39 between which and stub-shafts 40 fixed in projections 23^a from the lower ends of the end plates 23 are located compression springs 41. These springs, which are provided with telescoping guide members 42, tend to hold the rod 33 and the bridging contacts carried thereby in their upper or open position, as shown in Figs. 1 and 2. 20 A shaft 43 is mounted in bearings 44 at the upper ends of the end plates 23, and has loosely mounted on it beyond the bearing at each end two links 45 and 46, the lower ends of which are pivoted to links 47 and 48 loosely mounted on each rod 35. The links 35 45 and 47, and 46 and 48, form oppositely disposed toggles connecting the shaft 43 with the rods 35. Fixed on the shaft 43 near each set of links 45 and 46 is a collar 49 carrying an arc-shaped member 50 which 30 extends over the links 45 and 46 and nearly engages both of them when the switch is in open position as shown in Fig. 2. It is by means of this arc-shaped member 50 that the switch is operated when the shaft 43 is rotated. The ends of the shaft 43 are connected by tongue and groove couplings 51 to stub shafts 52 and 52^a mounted in bearings 53 in the frame 10, the tongues and grooves of these couplings being vertical to 40 allow the removal of the removable switch unit only when the switch is open. The shaft 52^a is preferably biased to this position by a light spring 54. The shaft 52 has fixed to it a collar 55 carrying the operating handle 56, the latter being pivoted on the collar 55 so that it may be moved into and out of engagement with notches in the locking plate 57. This locking plate 57 may be mounted on the frame 10 or on a switch board, the shaft 52 in the latter case extending through the switch-board or being suitably mechanically connected to a similar shaft located on the switch-board and carrying the operating handle 56. The inclosure 50 of the switch is completed by a cover 58.

When the switch is in open position, and then only, the couplings 51 allow the removable unit to be removed from and replaced in the tank, the cover 58 being first removed to allow access. As the removable unit is lifted from the tank, the contact fingers 26 leave the switch terminals 16 without disturbing the latter and without arcing. As the removable unit is replaced in the tank, the contact fingers 26 reengage the switch terminals 16, the spring contact fingers 26 being deflected sufficiently to cause firm engagement. When the switch unit is fully in place in the tank, it may be fastened there by any suitable means, as by bolts 59. When 70 the switch is open the operating handle 56 is in a central position, indicated in Fig. 2. Upon moving the handle 56 in either direction, the arc-shaped member 50 is brought into engagement with either the links 45 or 75 the links 46, causing the engaged links to rotate with the operating handle 56 and the shafts 52 and 43. Assume that the handle 56 is turned in a clockwise direction, as indicated in Fig. 3. The clockwise rotation of 80 the links 46 pushes the links 48, and through them the rods 35, to the left, the springs 41 holding the rollers 36 on the rods 35 against the upper or outer surfaces of the slots 37. The reactions of the various forces cause 85 the cross-heads 34 and the parts carried thereby to swing to the left (or counter-clockwise) on a constantly shortening radius about the stub shafts 40 until the projections 60 on the cross-heads 34 strike the guide faces 61 in the end plates 23. The continued movement of the shaft 43 then superimposes upon such rotation about the stub shafts 40 a clockwise rotation about the rods 35 as an axis, until the arms 38 and the cross-head 100 34 are again brought to the vertical position. By this time the rollers 36 have reached the left hand vertical portions of the slots 37. The still continued movement of the shaft 43 now moves the cross-head 34 and the 105 parts attached thereto vertically downward by a motion of pure translation, the two contacts 30 on each bridging member engaging the middle and left contacts 26 respectively of the corresponding poles of the switch and 110 finally reaching the position shown in Fig. 3. The closing movement of the switch is limited by the engagement of a projection 62 from the arc-shaped member 50 with the head of one of the adjusting screws 63. The 115 switch may be locked in closed position by the engagement of a tooth on the operating handle 56 with a suitable notch 64 in the locking plate 57. With the switch in closed position, the removable unit cannot be removed because of the inclined positions of the tongues and grooves of the couplings 51. 120 To open the switch the tooth on the operating handle 56 is disengaged from the notch 64. The springs 41 then expand and force 125 130

the movable switch parts upward to the open position, the opening movement of the switch parts being the reverse of their closing movement. Any arcs which occur are merely momentary because of the quick opening action which is obtained, and are prevented from striking over from one contact to another by the insulating barriers 29. To close the switch in the other direction, the handle 56 is moved in a counter-clockwise direction from its central or off position, thereby causing the engagement of the arc-shaped member 59 with the links 45 and moving the movable switch parts to the right hand closed position, with the bridging contacts connecting the middle contacts 26 with the corresponding right hand contacts 26.

Various modifications may be made in the precise arrangement shown and described, and I aim to cover all such modifications which do not involve a departure from the spirit and scope of my invention as set forth in the appended claims.

What I claim as new is:

1. In a switch, an oil tank, two bars in said tank near the bottom thereof, one or more cross-bars connecting the first-named bars, and a plurality of switch terminals mounted on top of said cross-bars and insulated therefrom, in combination with a removable switch unit comprising a frame removable from and replaceable in said tank, fixed contacts carried by said frame and located directly above and in engagement with the switch terminals when the removable frame is in place in the tank, and one or more movable contacts mounted on said frame and coöperating with said fixed contacts.

2. In a switch, the combination of an oil tank, a frame therein comprising a plurality of bars and one or more cross-bars connecting the first-named bars, a plurality of insulators mounted on said cross-bars, switch terminals mounted on said insulators, and switch contacts movable into and out of engagement with said switch terminals and when engaging the latter subjecting said insulators to compression only.

3. In a switch, the combination of an oil tank, two bars in said tank, one or more cross-bars connecting the first-named bars, a plurality of insulators mounted on said cross-bars, a switch terminal mounted on such insulator, and a removable switch unit comprising a frame removable from and replaceable in said tank, fixed contacts carried by said frame, and movable contacts co-operating with said fixed contacts, said movable contacts engaging said fixed contacts and said fixed contacts engaging said switch terminals when the removable switch unit is in place in the tank and the switch is closed, the stresses on such insulators under

such conditions being one of compression only.

4. In a switch, the combination of an oil tank, switch terminals in said tank near the bottom thereof, and a removable switch unit 70 comprising a frame including a bottom plate of insulating material, fixed contacts mounted in said bottom plate and projecting on both sides thereof, said fixed contacts being directly above and their downwardly 75 projecting parts engaging said switch terminals when the removable switch unit is in place in the tank, and one or more movable contacts coöperating with the upwardly projecting parts of said fixed contacts. 80

5. In a switch, switch terminals suitably mounted in a fixed position, in combination with a removable switch unit comprising 85 a plate of insulating material, fixed contacts mounted in said plate and projecting on both sides thereof, the parts of said fixed contacts which project on one side of said plate engaging said switch terminals when the removable switch unit is in place, and one or more movable contacts coöperating 90 with the parts of said fixed contacts which project on the other side of said plate, the switch terminal engaging part and the movable contact engaging part of each of said fixed contacts being in alinement with the 95 corresponding switch terminal.

6. In a switch, the combination of a support, switch terminals mounted thereon, a movable plate of insulating material, contacts mounted in said plate and each extending through said plate on opposite sides thereof, said contacts in all positions of said plate being in alinement with said switch terminals and movable into and out of engagement therewith, and movable contact members having portions engageable with said contacts mounted in said plate and movable into and out of engagement therewith in alinement with said switch contacts. 100

7. In a switch, the combination of stationary contacts, a movable support, intermediate contacts projecting from both sides of said movable support, the intermediate contacts on one side of said support engaging said stationary contacts, and movable bridging members having contact portions less in number than the intermediate contacts and engageable with a plurality of but less than all of the intermediate contacts on the other side of said support, and operating means for causing each bridging member to engage a plurality of said intermediate contacts. 110

8. In a switch, the combination of a movable supporting plate, conductors mounted in said plate and projecting on both sides thereof, spring fingers mounted on the projecting parts of said conductors on each side of said plate, and contact members a portion 125

- of which coöperate with the spring contacts on one side of said plate and another portion of which are movable relatively to the spring contacts on the other side of said plate.
9. In a switch, the combination of a movable supporting plate, conductors mounted in said plate and projecting on both sides thereof, a pair of opposed spring fingers mounted on each of said conductors on each side of said plate, and wedge-shaped contact members coöperating with and movable relatively to the spring contact fingers on each side of the plate and when in engagement with said spring contact fingers being located between the two fingers of a pair and spreading them apart.
10. In a switch, the combination of an oil tank, two bars in said tank, one or more cross-bars connecting said first-named bars, three switch terminals mounted on each of said cross-bars and insulated therefrom, and a removable switch unit comprising a frame removable from and replaceable in said tank, contacts carried by said frame, there being one of said contacts for each switch terminal, and a bridging contact for each set of three switch terminals, each of said bridging contacts engaging two of the first-named contacts and the latter engaging the corresponding switch terminals when the removable switch unit is in place in the tank and the switch is closed.
11. In a switch, the combination of an oil tank, two bars in said tank, one or more cross-bars connecting said first-named bars, three switch terminals mounted on each of said cross-bars and insulated therefrom, and a removable switch unit comprising a frame removable from and replaceable in said tank, contacts carried by said frame, there being one of said contacts for each switch terminal, a bridging contact for each set of three switch terminals, each of said bridging contacts engaging two of the first-named contacts and the latter engaging the corresponding switch terminals when the removable switch unit is in place in the tank and the switch is closed, and means for moving said bridging contacts into engagement with different pairs of said first-named contacts.
12. In a switch, one or more rows of switch terminals, there being three terminals in a row, in combination with a removable switch unit comprising a row of contacts for each row of terminals, there being one of said contacts for each switch terminal, and a bridging contact for each row of said first-named contacts, each bridging contact engaging the middle one and one of the end ones of the corresponding row of first-named contacts and the contacts engaged thereby engaging said switch terminals when the removable switch unit is in place and the switch is closed.
13. In a switch, one or more rows of switch terminals, there being three terminals in a row, in combination with a removable switch unit comprising a row of contacts for each row of terminals, there being one of said contacts for each switch terminal, a bridging contact for each row of said first-named contacts, each bridging contact engaging the middle one and one of the end ones of the corresponding row of first-named contacts and the contacts engaged thereby engaging said switch terminals when the removable switch unit is in place and the switch is closed, and means for moving said bridging contacts into engagement with the middle and different end ones of the corresponding rows of first-named contacts.
14. In a switch, the combination of terminal contacts one or more rows of intermediate contacts coöperating therewith, there being three contacts in a row, a bridging contact for each row of said intermediate contacts, and means for moving said bridging contacts so that each bridging contact may engage the middle contact and either end contact of the corresponding row of intermediate contacts and for causing the engaging and disengaging movement between said bridging contacts and intermediate contacts to be one of substantially pure rectilinear translation.
15. In a switch, the combination of terminal contacts one or more rows of intermediate contacts coöperating therewith, there being three contacts in a row, a bridging contact for each row of said intermediate contacts, and means for moving said bridging contacts so that each bridging contact may engage the middle contact and either end contact of the corresponding row of intermediate contacts and for causing the engaging and disengaging movement between said bridging contacts and intermediate contacts to be one of substantially pure rectilinear translation while the intermediate part of the movement of the bridging contacts includes a movement of rotation.
16. In a switch, terminal contacts, a row of three contacts coöperating therewith, a bridging contact which is normally out of line with said three contacts, and means for moving said bridging contact so that it will engage the middle one and either end one of said row of contacts and for causing the engaging and disengaging part of such movement to be a substantial movement of pure translation substantially at right angles to the line of such row of contacts.
17. In a switch, terminal contacts, a row of three contacts coöperating therewith, a bridging contact which is normally out of line with said three contacts, and means for moving said bridging contact so that it

- will engage the middle one and either end one or said row of contacts and for causing the engaging and disengaging part of such movement to be a substantial movement of pure translation substantially at right angles to the line of such row of contacts and the intermediate part of such motion to be partly rotational.
18. In a switch, the combination of three contacts, a bridging contact, said bridging contact being normally out of engagement with all the contacts of said row and with its middle point substantially equidistant from the two end contacts, means for moving said bridging contact first by a movement including one of rotation to a position where its middle point is substantially equidistant from the middle contact of the row and one of the end contacts, and then by a movement of substantially pure translation into engagement with said middle and end contacts.
19. In a switch, the combination of terminal contacts, a row of three intermediate contacts coöperating therewith, a bridging contact, said bridging contact being normally out of engagement with all the contacts of said row and with its middle point substantially equidistant from the two end contacts, and means for moving said bridging contact first to a position where its middle point is substantially equidistant from the middle contact of the row and one of the end contacts, and then into engagement with said middle and end contacts.
20. In a switch, the combination of terminal contacts, a row of three intermediate contacts coöperating therewith, a bridging contact normally out of engagement with all the contacts of said row and with its middle point substantially equidistant from the end contacts thereof, a spring tending to hold said contact in such position, operating mechanism including guiding surfaces for moving said bridging contact from such normal position to a position in which it bridges the middle contact of the row and one of the end contacts thereof, the last part of such movement being one of substantially pure translation at right angles to said row of contacts.
21. In a switch, the combination of three contacts, a bridging contact the middle point of which is normally substantially equidistant from two of such contacts, an operating mechanism for moving said bridging contact so that its middle point is first made equidistant from one of said two contacts and the third contact and at a different distance from the other of said two contacts and is then moved by a movement of substantially pure translation into engagement with the two contacts from which it has been made equidistant.
22. In a switch, the combination of a group of more than two contacts, a bridging contact, an operating shaft, a pair of oppositely disposed toggles connecting said bridging contact and said operating shaft, a clutch for locking said two toggles to said operating shaft as the latter is turned in opposite directions respectively from a normal position, and guides coöperating with said bridging contact and acting to cause it to engage different pairs of said group of contacts according as the shaft is turned in one direction or the other.
23. In a switch, the combination of a group of more than two contacts, a bridging contact, an operating shaft, a pair of oppositely disposed toggles connecting said bridging contact and said operating shaft, a clutch for locking said two toggles to said operating shaft as the latter is turned in opposite directions respectively from a normal position, and guides coöperating with said bridging contact and acting to cause it to engage different pairs of said group of contacts according as the shaft is turned in one direction or the other and to make the final part of such movement of the bridging contact a movement of substantially pure translation.
24. In a switch, the combination of a group of more than two contacts, a bridging contact, an operating shaft, a pair of oppositely disposed toggles connecting said bridging contact and said operating shaft, a clutch for locking said two toggles to said operating shaft as the latter is turned in opposite directions respectively from a normal position, and guides coöperating with said bridging contact and acting to cause it to engage different pairs of said group of contacts according as the shaft is turned in one direction or the other and to make the final part of such movement of the bridging contact a movement of substantially pure translation and the first part a movement of combined rotation and translation.
25. In a switch, the combination of fixed contacts, a movable contact, an operating shaft, a pair of oppositely disposed toggles loosely connected to said operating shaft and to said movable contact, a spring tending to hold the operating shaft and movable contact in normal position, a clutch which when the shaft is turned in opposite directions locks said two toggles respectively to said shaft so that the motion from the shaft is communicated to the movable contact, and guides coöperating with said movable contact for causing it to engage different fixed contacts when the operating shaft is moved in opposite directions.
26. In a switch, the combination of fixed contacts, a movable contact, an operating shaft, a pair of oppositely disposed toggles

loosely connected to said operating shaft and to said movable contact, a spring tending to hold the operating shaft and movable contact in normal position, a clutch 5 which when the shaft is turned in opposite directions locks said two toggles respectively to said shaft so that the motion from the shaft is communicated to the movable contact, and guides coöperating with said movable contact for causing it to engage different fixed contacts when the operating shaft is moved in opposite directions and for causing the final engaging movement of said movable contact to be one of substantially pure translation.

27. In a switch, the combination of fixed contacts, a movable contact, an operating shaft, a pair of oppositely disposed toggles loosely connected to said operating shaft 20 and to said movable contact, a spring tending to hold the operating shaft and movable contact in normal position, a clutch which when the shaft is turned in opposite directions locks said two toggles respectively to said shaft so that the motion from the shaft is communicated to the movable contact, and guides coöperating with said movable contact for causing it to engage

different fixed contacts when the operating shaft is moved in opposite directions and 30 for causing the final engaging movement of said movable contact to be one of substantially pure translation and the first part a movement of combined translation and rotation.

35

28. In a switch, the combination of terminal contacts, one or more rows of intermediate contacts coöperating therewith, there being three contacts in a row, a bridging contact for each row of said intermediate 40 contacts, and means for moving said bridging contacts so that each bridging contact may engage the middle contact and either end contact of a corresponding row of intermediate contacts and for causing the engaging and disengaging movement between said bridging contacts and intermediate contacts to be one of substantially pure translation.

45

In testimony whereof I affix my signature, in the presence of two witnesses.

BRADLEY HASKINS.
